WARP DRAWING APPARATUS AND METHOD

Erwin C. Kieke, Dallas, Tex., assignor to The Dallas Cotton Mills Company, Dallas, Tex., a corporation of Texas

Application January 3, 1939, Serial No. 249,009

6 Claims. (Cl. 28—44)

This invention relates to a drawing-in machine and more especially to a machine which has means for facilitating the preparation of warps for installation in a loom. More specifically, the invention relates to a machine which is used for drawing the free ends of a warp beam through the drop wires, heddle eyes, and loom reed prior to these parts being installed in a loom for use.

10 Heretofore, various attachments have been provided for drawing in warp ends through cotton harness. Since this harness is made from flexible material, there is practically no danger of the drawing-in needle becoming broken, should the cotton harness eye be improperly centered at the time the needle reciprocates. Due to the fact that these harness are constructed of cotton or other fibrous materials their life is necessarily limited, and as a result, the harness has to be replaced after being used a comparatively short length of time. Replacing these cotton harness is expensive, therefore the recent trend has been in favor of using steel heddles in place of cotton harness, because they have a much greater life.

15 By using steel heddles, however, it has necessitated that many manufacturers discontinue the use of the old drawing-in frames which were used on the cotton harness, because the eyes of the steel heddles could not be properly positioned so that the needle would penetrate the eye each time. Of course, if an eye should not be properly centered and the needle should contact the heddle at one side of the eye, the needle would be broken.

20 It is, therefore, an object of this invention to provide an improved means for supporting steel heddles as they are advanced to drawing-in position in such a manner that the eyes therein will be positively held in position, so that the needle in a drawing-in frame for cotton harness will penetrate the same upon each reciprocation thereof. The present drawing-in frame embodying my invention has associated therewith, first, apparatus for supporting the loom reed in such a manner that the dents will be properly centered and opened, second, an improved means for advancing steel heddles one at a time to drawing-in position, third an improved means for gripping each heddle above and below the eye so that the eye will be properly positioned for the needle to penetrate the same, fourth means for positioning drop wires and finally means for drawing warp ends through successive groups of the above-named loom parts.

25 It is another object of the invention to provide

a drawing-in frame provided with means for receiving and supporting the heddles and heddle bars from a heddle frame, and means for advancing, positioning and holding the heddles while they are pierced by the threading needle of the drawing-in frame, with means for supporting the heddles as a unit while they are again positioned in the heddle frame of a loom.

Some of the objects of the invention having been stated, other objects will appear as the description proceeds when taken in connection with the accompanying drawings, in which—

Figure 1 is a plan view of an ordinary cotton harness drawing-in machine with portions thereof omitted but showing portions of my invention embodied therein;

Figure 2 is a schematic isometric view showing the manner in which the drawing-in needle of the machine shown in Figure 1, operates to draw a warp end through a drop wire, heddle eye, and a loom reed;

Figure 3 is a transverse vertical sectional view taken along the line 3—3 in Figure 1;

Figure 4 is an enlarged sectional plan view taken along the line 4—4 in Figure 3;

Figure 5 is a sectional view with certain portions omitted, taken along the line 5—5 in Figure 3 showing cam means for gripping the heddle above the eye and a bottom heddle holder therebetween for engaging the heddle below the eye;

Figure 6 is an elevation of my improved frame for holding the heddles while the ends are being drawn therethrough, said view being taken along the line 6—6 in Figure 3;

Figure 7 is an end view, looking at the left-hand end of Figure 6;

Figure 8 is an enlarged view of the central portion of Figure 3, looking at the suspended end of the warp worms, showing the heddles, bottom heddle holder and drawing-in needle, but omitting the supporting frame;

Figure 9 is an isometric view of the bottom heddle holder;

Figure 10 is an enlarged view taken along the line 10—10 in Figure 3, showing the cam means on the warp worm turned to gripping position with the heddle and positively holding it in position so that its eye can be penetrated by the needle and also showing the bottom heddle holder in an engaging position;

Figure 11 is an enlarged sectional plan view taken along the line 11—11 in Figure 10;

Figure 12 is an elevation of an ordinary heddle frame as it appears removed from a loom with the central portion thereof broken away, show-

50

55

ing the position of the heddles and the heddle bars prior to being installed in the frame shown in Figure 6.

Referring more specifically to the drawings, 5 the numeral 10 denotes a suitable framework for a drawing-in machine which has a conventional pattern mechanism 11 and a needle head base 12 (Figure 1). This base has a needle head 14 mounted thereon, in which is slidably mounted 10 for reciprocatory motion, a needle 15 (Figure 3). The needle is reciprocated by a suitable link 16, one end of which is secured to the needle as at 17 and its other end secured to the upper end of a vertically disposed lever 19 as at 20. The 15 lever 19 is pivoted as at 22. A link 23 has one end thereof secured to an intermediate portion of the lever 19 and its other end eccentrically secured to rotatable disk 24. It is therefore seen that as the disk 24 is rotated that the needle 15 20 will be caused to reciprocate back and forth in Figure 3.

Mounted in the framework 10 is a suitable threaded shaft 27 which is engaged by a split nut 28 and this nut is secured to base member 25 12 (Figures 1 and 3). As the shaft 27 rotates, the needle head 14 and its associated parts are moved to the left in Figure 1. A square drive shaft 30 is also rotatably mounted in the framework 10 and this square shaft has slidably mounted thereon a gear 31 which meshes with a larger gear 32, said larger gear being adapted to drive the mechanism for actuating the parts of the needle head.

The base member 12 also has mounted thereon 35 a bracket 35, which bracket has worm supports 36, 37, 38, 39 and 40 extending upwardly therefrom. The member 36 also supports a reed guide 42, and a needle guide 43. Needle guides 44 and 45 are supported by upstanding members 37 40 and 39, respectively.

The outermost end of bracket member 35 has 45 extending upwardly therefrom a bracket 46 which supports drop wire turn worms 47, which worms are adapted to move drop wires 48 toward the observer in Figure 3 and turn the same in such a position that the thread eye 48a in the central portion thereof will be disposed at right angles to the path of travel of the needle 15. Suitable needle guides 50 are supported by the upper portion of bracket 46.

A warp rod 51 is disposed to the right and slightly above the drop wire turn worms 47 in Figure 3. This warp rod has a spiral groove 52 therein which feeds the warp ends 53 toward the 55 observer in Figures 2, 3 and 4, and in such a position that the needle 15 will engage the same one at a time when it is in an extended position. The warp ends 53 are drawn from a beam 54 disposed upon a suitable truck 55. These warp 60 ends are clamped directly above the beam by a suitable clamping mechanism 56, after which the warp ends are drawn over the rod 51 and then the ends are again clamped in a clamping member 57. The clamps 56 and 57 are supported 65 by a warp clamp bracket 60.

The framework 10 also has a superstructure 61, said superstructure comprising a track member 62 upon which reed clamp brackets 63 are adapted to travel, only one being shown. These 70 brackets support loom reed 64, the dents of said reed being adapted to be opened (Figures 2 and 3), by a suitable reed opener 65. Each time the needle 15 reciprocates, it penetrates needle guide 43, loom reed 64, the eye in one of the heddle 75 bars 18, needle guides 44 and 45, drop wires 48,

needle guides 50, after which a quarter turn is imparted to the needle by a conventional mechanism so that the hook on the end of the needle will be adjacent the advancing warp ends 53 as shown in Figure 4. When the warp rod has 5 turned sufficiently to place the leading warp end 53 in the hook of the needle, the needle is drawn to the left in Figures 3 and 4. After travelling a slight distance, a quarter turn in the opposite direction is again imparted to the needle to restore the same to normal position as shown in Figure 3 at which time the needle hook will be disposed upwardly. A suitable stripper 70 is provided to remove the loose end of the thread which is left upon the hook after the various 15 members have been threaded.

It is therefore seen that the needle 15 reciprocates back and forth, first to the right and then to the left in Figures 3 and 4 to engage an end 53 and draw it through the drop wires 20 48, the loom reed 64, and one of the heddle bars 18 which will be presently described. A suitable conventional advancing mechanism is provided for advancing each of these respective members except the heddles to their proper positions upon 25 each reciprocation of the needle. The novel heddle advancing means will be later described. The structure thus far described is conventional, but it is thought that this much of the old structure should be disclosed and described in order 30 to more clearly illustrate my present invention.

As heretofore stated, various types of drawing-in mechanism have been employed for a long time in drawing-in the warp ends where cotton harness were used. Due to the necessity of having 35 a harness that would last longer, it has been common practice of recent years to use steel heddles. Since steel heddles are made of rigid material, it has been impossible to use the cotton harness drawing-in machine because a slight 40 misplacement of the heddle eye would cause a broken needle and mis-threading. Therefore, when it has been necessary to draw warp ends through steel heddles, this type of machine has been abandoned and tying-in machines have 45 been used instead. I have provided a simple and inexpensive means which may be applied on a drawing-in mechanism of this type, said mechanism being capable of properly positioning the eyes of steel heddles so the needle 15 50 will penetrate these eyes each time.

Figure 12 shows an ordinary harness frame 75 as it appears when removed from a loom. This frame has removably mounted therein heddle bars 76 and 77 which in in turn support the ends 55 of heddles 78. Each heddle is formed from an elongated flat metallic piece which has an eye portion bent to an angle of approximately thirty degrees with the flat side, thereof. An eye 79 is punched through this bent portion so that warp 60 ends 53 may be drawn therethrough by the needle 15 (Figure 11).

The ends of the heddle bars 76 and 77 have suitable holes therein which holes are penetrated by the ends of spring clips 80 and 81, respectively. 65 When these spring clips are removed from the holes in the ends of the heddle bars, these bars together with their associated heddles 78, may be removed from the frame 75. The heddles 78 are separated by the coils of a helical spring 82. It 70 is customary to apply these springs as a permanent attachment to the harness, a cord 83 being drawn through the coils to keep the heddles in place in the spring when the harness is in the loom. When the harness is used in the loom 75

a rod 84 is inserted through the spring for holding the latter near the upper side of the harness. The cord 83 is tied in the manner shown in Figure 12 to hold the coiled spring 82 in elevated position.

When preparing for the drawing-in operation, the spring 82 is moved to the position shown in Figure 6 at which time the coil spring 82 is disposed a slight distance above the heddle eyes 79. Before effecting the drawing-in operation, the heddle bars 76 and 77 together with their associated heddles are removed from the frame 75 and placed in a frame 87, shown in Figure 6. This frame comprises upper and lower T-shaped rails 88 and 89, the ends of said rails being joined together by suitable I-beam sections 90 and 91. Disposed between the flanges of the I-beam section 90 and the top and bottom rails 88 and 89 are blocks 92 and 93, and likewise disposed between the flanges of the I-beam section 91 and the top and bottom rails are similar blocks 94 and 95. The blocks 92 and 93 are secured to the top and bottom rails by means of suitable screws 97 and 98 respectively, and these same blocks are secured to the flanges of I-beam section 90 by means of set screws 100 and 101. The blocks 94 and 95 are secured to the top and bottom rails 88 and 89 by means of screws 102 and 103 respectively, and the flanges on the top and bottom of the member 91 are secured to blocks 94 and 95 by means of screws 104 and 105 respectively. Slidably mounted in blocks 92 and 93 are flat bars 108 and 109, said bars having pins 110 and 111 respectively therein which limit the movement to the right of these bars in Figure 6. The right-hand end of members 108 and 109 have laterally projecting pins 112 and 114 respectively therein which pins are adapted to penetrate the holes in the left-hand ends of heddle bars 76 and 77. The right-hand ends of the heddle bars 76 and 77 also have suitable holes therein which fit over pins 115 and 116, said pins being disposed in the left-hand end of slidably members 117 and 118, respectively. The members 117 and 118 are slidably mounted in blocks 94 and 95 as well as in blocks 120 and 121, which are secured to the upper and lower rails, respectively. The extreme right-hand ends of the members 117 and 118 are threaded so as to accommodate wing nuts 122 and 123. It is seen that when the heddle bars 76 and 77 are inserted in position that the holes in their ends will fit over pins 112, 114, 115, and 116. Then it is only necessary to tighten the nuts 122 and 123 to cause the necessary tension to be applied to these bars so that they will remain in the frame. Frame 87 has suitable holes 125 in the upper rail 88 which are adapted to be penetrated by hooks 126 (see Figures 3 and 6). These are ordinary harness hooks, the upper ends of which are supported by longitudinal tracks members 127. When the frames 87 are suspended in the manner shown in Figure 3, the heddles eyes 79 are at the same elevation as the needle guides 43 and 50, and the holes 48a in the drop wires 48. Therefore, a heddle eye must be moved longitudinally of the machine the proper amount each time the needle 15 reciprocates so that its eye will be in position to have a warp end 53 drawn therethrough. The frames 87 do not have as great vertical depth as the heddle frames 75 of the loom, the frames 87 being of such a height as to slidably confine the heddles and thus assure alinement of the eyes 79, with the needle

15, as their lower ends rest on the bottom rail 89. It will be noted by referring to Figure 3 that four heddle frames 87 such as indicated in Figure 6 are shown. Of course, a heddle from one of these frames is selected at a predetermined time which time is determined by the pattern mechanism 11. It is understood that only one heddle eye of the four frames will be in a position to be penetrated upon each swing of the needle 15, but the heddles which are in the various frames may be advanced at the desired time.

This advancing means comprises a suitable warp worm which turns at the desired time to position a heddle. In the present case, the four frames 87 which have the heddles 78 secured therein, have warp worms 135, 136, 137 and 138, the worms 135 and 136 forming a pair, and the worms 137 and 138 forming a pair. It will be noted (Figure 4) that each of the worms 135 and 137 have a right-hand spiraled groove 139 disposed therein, whereas each of the worms 136 and 138 have a left-hand spiraled groove therein. The worms 135, 136, and 137 and 138 are integral with rods 141, 142, 143 and 144, respectively, which rods extend from the pattern mechanism 11 as shown in Figure 1. When the frames 87 are suspended as shown in Figure 3, the leading ends, that is the ends nearest the observer, of the rods 141, 142 and 143 and 144 are inserted into the spiraled helical coils 82, and upon the rotation of these rods it is seen that the worms on each of these shafts will advance heddle 78 and force it to the right in Figure 1. In other words, for each revolution of a warp worm, a heddle is drawn into one of the grooves 139 and 140. However, it should be noted that due to the opposite pitch of the worms 135 and 136 it is necessary for the rods 141 and 142 to rotate in opposite directions in order to feed the heddles through the worms. After the worms have advanced a heddle 78 to the central position, as shown in Figure 10, the worm stops and the heddle remains in this centered position until the needle 15 penetrates the eye thereof. Then the worm makes another one-half revolution to move the heddle out of piercing position. At the same time the worm 136 makes a half turn to advance another heddle to piercing position.

By referring to Figure 11 it is seen that the eyes 79 are disposed at an angle α with the flat side of the heddle 78. This angle is usually about thirty degrees and if the heddle is held in this position there is very little difficulty in causing the needle 15 to properly penetrate the eye 79. However, due to the shape of the grooves in spiraled worms, there is a tendency for the heddle to rotate slightly in a counterclockwise manner in Figure 11 thereby causing the hole in the eye 79 to be improperly positioned for penetration. In order to insure that the heddle will be turned to the proper position when the eye reaches piercing position, as shown in Figures 10 and 11, it has been necessary to provide a suitable cam 147 on one of the walls of the groove 139. This cam surface partially closes the groove 139 so that the cam will engage one side of the heddle bar and turn it past dead center toward the opposite side of the groove 139. Immediately after the projection on the sidewall of the spiral groove engages a heddle and turns it, the flipper 150 engages the heddle and finishes turning the heddle to press it against the opposite wall of the spiral groove and straight wall 151a and 152a, thus preventing further axial movement of the heddle. This insures that the eye 79 will 75

always be positioned to allow the needle 15 to pass therethrough. The groove 140 in worm 136 has a similar cam surface 148. This cam likewise cooperates with the opposite side of the groove 140 and serves to turn the heddle in the proper direction.

The worms 135 and 138 inclusive work intermittently but it should be noted that it is when the cam surfaces 147 and 148 rotate to contacting position with the heddle 78 as shown in Figure 10 that the worms stop for a sufficient length of time to allow the needle 15 to draw an end therethrough. These worms are off set slightly with relation to each other to insure that while the 15 needle is penetrating the eye of a heddle which is centered, that the heddles which are disposed in the adjacent worms will be out of contacting position with the needle. By simply providing a cam means adjacent the spiraled groove the 20 axial play of the heddle is prevented and thereby the eye 79 is caused to be held in proper position so that the needle 15 may penetrate the same and draw an end therethrough.

Immediately after the contacting of the heddle 25 78 by either of the cams 147 or 148, an additional holding means 150 moves into contact with the heddle below the eye. By referring to Figure 8, the two positions that this bottom heddle holder 150 assume may be seen. In bold line position 30 the heddle holder is in normal position; whereas in dotted line position, it is engaging a heddle 78 on an adjacent frame. This bottom heddle holder 150 has notches 151 and 152 therein which contact the heddle bar 78 immediately after the 35 contacting of the upper portion of the heddle bar by the cams 147 and 148. By virtue of the shape of this notch, heddle bars 78 are firmly engaged (Figure 11) so that the lower portion of the heddle will be supported and held in position. 40 These notches 151 and 152 have one sidewall 151a and 152a which is at a right angle to the axis of rotation, and the other sidewall 151b or 152b is sloping, the sloping side being adapted to contact the heddle and force it against the sidewall 45 151a or 152a to insure that the heddle will be in piercing position. This bottom heddle holding means is mounted on the end of a shaft 153 which extends into the pattern mechanism 11. The direction that this shaft oscillates is dependent entirely upon the frame from which heddle 50 eye 79 has been selected to be penetrated by the needle 15. Likewise the warp worms 137 and 138 have cam surfaces 147 and 148, respectively, said cam surfaces and worms being identical in 55 all respects to the cam surfaces and worms previously described.

Each of the worm rods 141 and 144 inclusive has a rotatable fitting 155 secured on the end thereof, said fitting having an enlarged hole 156 therein with a longitudinal slot 157 communicating with this hole. When the heddle frame 87 is first placed in position within the drawing-in frame as shown in Figure 3, the ends of the rods 141, 142, 143 and 144 are inserted into a helical 60 coil 82, so that the heddles may be moved one at a time into piercing position. As these heddles are pierced and threaded, they are advanced toward the observer in Figures 3 and 4 along with the helical coil 82.

70 In order that this coil may be properly supported after it has advanced off of the ends of the rods 141 and 144 inclusive, a suitable cord such as indicated by reference characters 83 (Figure 12) has one end thereof knotted and fastened into the fitting 155, and as the heddles are

advanced they are pushed onto this cord. When the entire frame has been threaded, then a suitable rod 84 is inserted into this coil and then the coil and cord are lifted until they assume the position as shown in Figure 12 relative to the 5 upper heddle bar 76, after which the cord 83 is tied at each end to hold the rod 84 and coil spring 82 in position.

It is, therefore, seen that I have provided a simple means for supporting steel heddles above 10 and below the eyes in such a manner that the same may be accurately penetrated by the drawing-in needle on a conventional cotton harness drawing-in frame. This means although simple, has served a long-felt need in that it has 15 made useful machines out of obsolete cotton drawing-in frames. With this improvement, it is possible to draw in warp ends through steel heddles in just as an effective manner as these ends have been heretofore drawn through the eyes of 20 the cotton harness.

In the drawings and specification, there has been set forth a preferred embodiment of the invention, and although specific terms are employed they are used in a generic and descriptive 25 sense only and not for purposes of limitation, the scope of the invention being set forth in the appended claims.

I claim:

1. In a warp drawing-in frame having means 30 for holding and feeding the warp ends and means for holding drop wires and loom reeds and heddles and a reciprocating needle for penetrating the reed, the heddles, the drop wires and engaging the warp ends one at a time and drawing 35 the same through the drop wires, the heddles and the reed, a frame, means for securing heddle bars from a steel loom heddle in said frame to support steel heddles in the frame, means for advancing the heddles in said frame one at a time, 40 comprising a rotatable member having a spiral groove therein, said groove having a projection on one of its sidewalls for engaging a heddle and turning the same when it has reached a position to be pierced by the needle, and means 45 for also engaging the heddle turned by said projection and turning it until the heddle rests against the sidewall of the spiral groove opposed to the projection, to insure that the eye in the heddle will be in alignment with the path travelled 50 by the needle.

2. In a drawing-in frame having a needle for drawing warp ends, a plurality of frames disposed within the drawing-in frame, each frame having bottom and top rails and a pair of end rails, means disposed on one end of the frame for engaging one end of a pair of heddle bars removed from a steel heddle frame of a loom, means on the other end of the frame for engaging the other ends of the heddle bars and imparting 60 tension thereto to confine the heddle bars with their heddles to rest on the bottom rail of the frame in the drawing-in machine, and the top rail of the frame being in close proximity to the upper ends of the heddles, whereby substantial 65 vertical movement of the heddles will be prevented to insure that the eyes in the heddles will be on the same level as the path of travel of the needle of the drawing-in frame.

3. In a drawing-in frame provided with a 70 drawing-in needle and having a plurality of frames disposed in parallel spaced relation to each other, means in each frame for receiving and confining the heddle bars and heddles removed from a steel heddle frame in a loom, each 75

- of the heddles having an eye therein, a coiled spring disposed adjacent the eyes of the heddles and separating the heddles, a rod disposed in said coiled spring and having an enlarged portion 5 thereon provided with a spirally disposed groove, in which the heddles are adapted to be disposed, means for intermittently imparting rotation to the rod to advance the heddles towards the point traversed by the needle, one of the sidewalls of 10 the groove having a projection thereon for imparting axial movement to a heddle, and movable means for engaging the heddle adjacent to but on the other side of the eye after it has been turned by engagement with said projection, for 15 further turning the heddle and holding the heddle against the sidewall of the groove which is opposed to the projection to insure that the heddle eye will be in position to be traversed by the needle.
- 20 4. In a drawing-in frame having frames for supporting a plurality of sets of heddle bars and steel heddles removed from the heddle frames of a loom, a worm having a spiral groove therein for contact with each set of heddles adjacent 25 eyes thereof, said drawing-in frame having a reciprocating needle for piercing the eyes of the heddles for drawing a warp thread therethrough, means for selectively turning one of the worms for advancing one heddle in one of the sets to a 30 position traversed by the needle, means associated with each worm for imparting axial movement to its heddle advanced into the path of travel of the needle, and movable means for engaging the heddle at a point on the other side of 35 the eyes from where the worm contacts the heddles after it has had axial movement imparted thereto, for further turning the heddle and holding it in fixed position while the needle pierces the eye of the heddle.
- 40 5. In a warp drawing-in frame provided with a reciprocating needle and means for holding and advancing a reed, and means for holding and advancing drop wires, and means for advancing the warp, so as to position the reed, the drop wires and the warp in alinement with the path 5 of the needle, a plurality of frames disposed in the drawing-in frame and having means for receiving and holding heddle bars and steel heddles removed from the heddle frames in a loom, a worm member associated with each set of heddles, 10 a pattern means controlling rotation of the worm members for advancing one heddle at a time in one of the frames prior to each reciprocation of the needle, said worm member having a spiral groove therein for engaging and advancing the 15 heddles, one of the sidewalls of said groove having a projection thereon for turning a heddle, and a member movable into engagement with a turned heddle for completing the turning movement and holding it against the side of the wall 20 of the groove opposite said projection whereby the heddle eye will be disposed in the path of the needle so that the needle may pass successively through the reed, the heddle eye, a selected drop wire, and engage the selected warp end and draw 25 said warp end through said drop wire, the selected heddle, and the reed.
6. That method of drawing-in warp ends in a drawing-in frame which comprises removing the heddle bars and steel heddles from a heddle 30 frame in a loom and placing the same in a drawing-in frame, then advancing the heddles one at a time to drawing-in position, axially rotating the heddles one at a time and holding the advanced heddles in threading position, passing a warp thread through the heddle eyes, then removing the heddles from the drawing-in frame and replacing the same along the warp ends 35 therein in a loom heddle frame.

ERWIN C. KIEKE. 40
